UNITED STATES PATENT OFFICE.

CHARLES T. LAMONT, OF MILWAUKEE, WISCONSIN.

DESIGN FOR A HORN.

50,753.

Specification for Design.

Patented May 8, 1917.

Application filed March 10, 1917. Serial No. 154,046. Term of patent 14 years.

To all whom it may concern:

Be it known that I, CHARLES T. LAMONT, a citizen of the United States, residing at Milwaukee, in the county of Milwaukee and State of Wisconsin, have invented a new, original, and ornamental Design for Horns, of which the following is a specification, reference being had to the accompanying drawing, forming part thereof.

The figure is a side elevation of a horn illustrating my new design.

I claim:

The ornamental design for a horn, as shown.

In testimony that I claim the foregoing I have hereunto set my hand at Milwaukee, in the county of Milwaukee and State of Wisconsin, in the presence of two witnesses.

CHARLES T. LAMONT.

Witnesses:

FRANK S. RATCLIFFE,
M. E. DOWNEY.
